UNITED STATES PATENT OFFICE.

WILLIAM MILLIN DUNCAN, OF ALTON, ILLINOIS.

FURNACE.

1,145,573.

Specification of Letters Patent.

Patented July 6, 1915.

Application filed April 13, 1914. Serial No. 831,443.

To all whom it may concern:

Be it known that I, WILLIAM M. DUNCAN, a citizen of the United States of America, and resident of Alton, in the county of 5 Madison and State of Illinois, have invented certain new and useful Improvements in Furnaces, of which the following is a full, clear, and exact description, reference being had to the accompanying drawings, forming 10 a part of this specification.

My invention relates to an air regulating device particularly adapted for use in furnaces provided with traveling chain grates.

The chain grates of mechanical stokers 15 are so constructed that it has heretofore been found quite difficult to regulate or control the admission of air to the fuel supporting grates, and owing to the lack of proper regulating devices, too much air is admitted 20 at some points on the grates while at other points the air supply is insufficient. One of the most undesirable features of the old structures is that more air is admitted into 25 the combustion chambers than is needed for the proper burning of the coal and the gases of combustion. The greatest quantity of air usually enters at the rear end of the grate where the grate links are separated from each other in passing around the supporting 30 wheels, and also through the rear portion of the grate where the fuel bed is almost entirely burned away. Under different operating conditions an insufficient or an excessive volume of air may enter the combustion 35 chamber at various different points, and the object of the present invention is the production of an air regulating device adapted to control the admission of air at various different points below the fuel sup- 40 porting grates.

In the preferred form of my invention a series of independently adjustable dampers are arranged below the fuel supporting grates, and these dampers may be adjusted 45 selectively to vary the air supply, thereby enabling the operator to secure the best results by controlling the admission of air throughout the fuel bed.

Figure I is a longitudinal section of a 50 furnace embodying the features of my invention. Fig. II is a transverse section taken through the upper row of grate bars and showing one of the dampers arranged below said grate bars.

55 In the accompanying drawings: A des-

ignates side frames provided with wheels B and arranged between furnace walls C.

1 designates a drive shaft mounted in the side frames at the front end of the furnace and 2 designates an idle shaft mounted in 60 side frames at the rear of the furnace. The drive shaft is provided with suitable drive wheels 3 and the idle shaft is provided with idle wheels 4. The wheels 3 and 4 support a chain grate D having an upper row of 65 grate bars 5 the bottom faces of which rest on rollers 6 and a lower row of grate bars 7 resting upon rollers 8. The rollers are mounted on rods 9 secured to the side frames A.

A series of damper stops 10 supported by the side frames A is arranged below the rollers 6, each of these damper stops being provided with flanges 11 and 12 adapted to engage damper plates 13. The damper plates are secured to damper shafts 14 journaled in the side frames and provided with non-circular ends 15 adapted to receive a damper operating device 16. The damper operating device I have shown is a socket 80 wrench adapted to pass through openings 17 in one of the furnace walls C, said openings being located directly opposite to the damper shafts 14. A closure plate 18 is preferably secured to a cross beam 18' at the rear of 85 the grate to prevent or control the escape of air at this point. The row of dampers 13 extends substantially from end to end of the grate, and any of these dampers may be adjusted to control the admission of air 90 below the upper row of grate bars 5. The damper stops 10, together with rollers 6, form the side walls of separate air inlet pas- 95 sageways 19 through which the air passes to the bottom face of the upper row of grate bars, and since the rollers 6 contact with said bottom face, the air entering one of said passageways cannot escape into any of the other passageways, nor can it escape from one of the passageways to the bottom 100 faces of the grate bars above another pas- sageway. The dampers preferably have no direct connection with the grate chain, and said chain is free to travel independently 105 of the dampers. The dampers may be ad- justed independently of each other and they may be maintained in different positions to effectively control the admission of air to the various inlet passageways 19. The chain grate preferably surrounds the row of 110

dampers as shown in Fig. I, and the closure plate 18 is preferably located adjacent to the damper at the rear end of row to prevent the escape of a large volume of air 5 at the rear of the dampers.

I claim:

1. In a furnace, a traveling chain grate structure comprising a lower row of grate bars and an upper row of grate bars adapted 10 to support the fuel, side frames supporting said chain grate structure, a series of partition members extending downwardly from the bottom face of said upper row of grate bars to provide a series of separate inlet passageways, said partition members including rollers extending across the grate structure, said upper row of grate bars being seated upon said rollers to prevent the escape of air from one of the passageways to the bottom faces 15 of the grate bars at the upper end of another of the passageways, a series of dampers extending across the grate structure between said upper and lower rows of grate bars, each of said dampers being adapted to 20 regulate the admission of air to one of said separate passageways, and means for adjusting said dampers independently of each other to positively regulate the admission of air at different points on the bottom face 25 of said upper row of grate bars.

2. In a furnace, a traveling chain grate structure comprising a lower row of grate bars and an upper row of grate bars adapted 30 to support the fuel, side frames supporting said chain grate structure, a series of partition members extending downwardly from the bottom face of said upper row of grate bars to provide a series of separate inlet passageways, said partition members including 35 damper stops extending across the grate structure and rollers extending across the grate structure, said upper row of grate bars being seated upon said rollers to prevent the escape of air from one of the passageways to the bottom faces of the grate bars 40 at the upper end of another of the passageways, a series of dampers extending across the grate structure between said upper and lower rows of grate bars, each of said dampers being adapted to regulate the admission 45 of air to one of said separate passageways, and means for adjusting said dampers independently of each other to positively regulate the admission of air at different points 50 on the bottom face of said upper row of grate bars.

WILLIAM MILLEN DUNCAN.
In the presence of—

LEO BERNER,
W. A. CANNON.
